UNITED STATES PATENT OFFICE.

RINHOLD W. KRENZ, OF TOLEDO, OHIO.

GARBAGE-INCINERATOR.

1,155,492.

Specification of Letters Patent.

Patented Oct. 5, 1915.

Application filed March 31, 1915. Serial No. 18,375.

To all whom it may concern:

Be it known that I, RINHOLD W. KRENZ, a citizen of the United States, and a resident of Toledo, in the county of Lucas and State of Ohio, have invented a certain new and useful Garbage-Incinerator; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates particularly to a garbage incinerator and has for its object the provision of an improved apparatus of this character which is simple and inexpensive in its construction, economical to operate and highly efficient in its operation, whereby to enhance the practicability and commercial value thereof.

20 Further objects and advantages of the invention will be apparent from the following 25 detailed description thereof.

The invention is fully described in the following specification, and while, in its broader aspect it is capable of embodiment in numerous forms, a preferred and one 20 modified embodiment thereof are illustrated in the accompanying drawings, in which,—

25 Figure 1 is a central vertical section of an apparatus embodying the invention. Fig. 2 is a cross-section thereof on the line x, x in Fig. 1. Fig. 3 is a side elevation of the apparatus with the top part partly broken away and slightly modified over the construction shown in Fig. 1.

30 The apparatus embodying the invention is preferably, but not necessarily, of circular form and has its body wall or shell composed of inner and outer walls 1 and 2 with a suitable heat insulating material 3, such, for instance, as asbestos, disposed therebetween. A bottom member 4 closes the bottom or lower end of the apparatus and has its top surface preferably of concaved form 45 for the purpose hereinafter described.

50 The top portion of the apparatus is provided with inner and outer walls 5 and 6, respectively, which have an insulating material 7 packed therebetween. The inner wall 5 extends inward from the upper end of the body wall and forms an entrance passage 8 to the fire chamber of the apparatus, said entrance passage being tapered to grad-

ually restrict it toward its upper end. A pipe or delivery chute 9 rises from the upper end of the passage 8 and is used when the apparatus is placed in the basement and it is desired to throw garbage therein from one or more floors above. In such case the delivery pipe 9 is provided in the rooms above, from which garbage or other matter is to be thrown therein, with doors 10.

60 The pipe 9 is provided at its lower end, in the present instance, within the passage 8 with a trap-door 11 which is pivoted to the upper portion of the apparatus top at one side of the pipe, as at 12, and is provided

65 without said pivot with a weighted arm 13 which normally acts to retain the door 11 in pipe closing position, as shown in Fig. 1.

70 When garbage has been delivered into the pipe 9 and falls onto the door 11, the weight thereof will cause a downward swinging of the door so as to dump the garbage into the fire chamber of the apparatus after which the door automatically closes to prevent fumes from passing upward through the 75 pipe 9 and into the rooms with which it

75 communicates. An exit pipe 14 for the fumes and gases leads through the top portion of the apparatus from the passage 8 therein and extends to any suitable point of 80 discharge. It is preferable to provide a communicating pipe, such as shown at 15, between the delivery pipe 9 and fume exit pipe 14 to permit any fumes which might enter or be present in the pipe 9 to pass therefrom into the pipe 14.

85 A gas burner 16 is provided in the lower portion of the fume exit pipe 14 to burn all gases of a combustible nature which may escape from the interior of the apparatus through the pipe 14.

90 In the lower portion of the apparatus, in vertically spaced relation to the bottom 4, is

95 a grate 17, which rests at its outer edges upon bracket members 18, and preferably has its central portion provided with an overturning or tiltable grate member 17^a to facilitate a dumping of ashes or other matter accumulating on the grate. Below the grate 17 is disposed a barred flooring 19 for supporting the ash pan 20.

100 The ash pan 20 is removable from the apparatus through doors 21 in the front thereof and has its bottom perforated to permit liquid matter therein to drain therefrom onto the concaved bottom 4.

105 A drainage pipe 22 leads from the bottom 4 to take care of such drainage. A water pipe 23 is disposed within

the lower drainage portion of the apparatus, being hung, in the present instance, on the bottom of the ash pan supporting floor 19 and is provided with perforations for 5 directing a multiplicity of streams of water against the bottom 4 for flushing purposes. Water is supplied to the flushing pipe 23 through a valved pipe 24.

In order that the garbage deposited in the 10 fire chamber of the apparatus may be held in spaced relation to the body drum of the apparatus and thereby permit the free circulation of air around the garbage, I provide grate bars 25, which rise from the outer edge 15 portion of the grate 17, extend to the top portion of the fire chamber and form a grate entirely around the central portion of the fire chamber, as indicated, thus providing the free space 26 between the body wall of 20 the apparatus and the grate bars 25. The grate bars 25 in reality form a fire pot within the apparatus which fire pot is provided with a multiplicity of vertically extending slots 27 to open communication between the 25 interior thereof and the space 26.

A gas manifold 28 extends around the lower portion of the apparatus and has pipes 29 extending at intervals therefrom through the side of the body wall and into 30 the interior of the fire box forming burners therein. The pipe 30, which feeds the burner 16, is also shown as leading from the manifold 28. Another pipe 31 extends from the manifold 28 through the body wall of 35 the apparatus and terminates at the center of the fire box in a burner 32. This burner and a portion of its pipe are inclosed by a tube 33, which tube stands upright within the fire box and has its lower end inclosing 40 the burner 32 and angling with the pipe 31 to adjacent the body wall of the apparatus, opening at its lower end into the space 26, whereby it may receive air therefrom. The upright portion of the tube 33 extends to or 45 near the top portion of the fire box and is tapered or gradually enlarges from its lower end upward, as shown. A conical cap 34 is provided on the top of the tube 33 to direct garbage falling thereon to one side or another of the tube. The hot gases within the tube 33 have their exit therefrom into the upper portion of the fire box through openings 35 in the upper portion of the tube. The purpose of tapering the tube 33 is to 50 prevent the garbage from packing closely around the tube as it settles within the fire box.

It is preferable to provide the upper portion of the body wall of the apparatus with 55 a door 36 through which matter may be thrown into the fire box. The apparatus shown in Fig. 3 is the same in construction as that just described except that it is not adapted to have garbage or other matter deposited therein from a floor above. In this

form 37 designates a hopper which is mounted on the conical top portion of the apparatus and has communication with the fire chamber thereof. The outer end of the hopper 37 is provided with a door 38 while the 70 inner end thereof is provided with a trap door 39 that is pivoted to automatically open when garbage is deposited thereon. A weighted arm 40 projects from the pivoted end of the trap door 38 and serves to normally hold the door in closed position. A fume exit pipe 41 leads from the hopper 37 into the main fume exit pipe 42 of the apparatus.

In the use of my improved garbage incinerator the garbage or matter to be burned is delivered into the fire box thereof either through the delivery pipe 9, the door 36, or the hopper 37, as the case may be, and if delivered into the fire box in considerable 80 quantity, it gathers around the center tube 33 in contact therewith. The flames from the pipes or burners 29 traverse up through the garbage and effect a burning of all combustible matter therein while the flame from the burner 32 within the tube 33 highly heats the tube 33 and serves to dry the central portion of the mass of garbage within the fire box. The heating of the central portion of the garbage in this manner very materially 90 facilitates a burning thereof as a more rapid drying of wet garbage is thereby effected. 95 There would be possible if no center heating column were provided. The grated side wall 25 of the box is also important, for if the mass of garbage within the fire box is firmly packed therein so that the fumes from the burners 29 cannot work up through the garbage, such fumes can work out through the slots 27 in the fire box wall and thence traverse upward through the space 26 and again enter the fire box at the upper portion thereof. Any ash resulting from the burning of the garbage is deposited in 100 the ash pan 20, and any liquid matter which may drain into the ash pan is permitted to drain from the pan through its perforated bottom and into the lower drainage portion of the apparatus from whence it passes to the sewer through the drainage pipe 22. When desired water may be turned into the flushing pipe 23 for the purpose of 105 flooding and cleaning out the lower drainage portion of the apparatus.

I wish it understood that my invention is 110 not limited to any specific construction, arrangement or form of the parts except in so far as such limitations are specified in the claims.

Having thus described my invention, what 115 I claim as new, and desire to secure by Letters Patent, is,—

1. In an apparatus of the class described, a fire chamber, a tube extending up within 120 said chamber and gradually enlarging from 125

the bottom to the top thereof, said tube having communication at its upper end with the upper portion of said chamber, and heating means interiorly of the tube.

5 2. In an apparatus of the class described, a fire chamber having a grated bottom, a tube extending from one side of said chamber to the center thereof adjacent to the grate and thence extending upward through 10 the central portion of the chamber to the upper part thereof and having its upper end opening into said chamber, and heating means disposed within said tube.

3. In an apparatus of the class described, 15 an outer casing, a fire box disposed within said casing and having a bottom grate and a side grating rising from the bottom grate in spaced relation to said casing, a tube extending from a point between said casing 20 and side grating through said grating to near the center of the fire box and thence extending upward through the central portion of the fire box and having its upper end in lateral communication with the upper end of the fire box chamber, and a 25 burner disposed in said tube for heating the wall thereof and for directing a spreading flame outward from the top of said tube over the top of matter disposed in the fire 30 box.

4. In an apparatus of the class described, a fire box, a tube extending from without said fire box transversely thereof to near its center and adjacent to its lower end, thence 35 extending upward through the central portion of the fire box chamber and having lateral communication at its upper end with the upper portion of the fire box chamber, and a burner disposed in the lower portion 40 of said tube.

5. In an apparatus of the class described,

a fire box, a tube extending from without the fire box transversely thereof to near the center thereof and thence extending upward through the central portion of the fire box 45 chamber and having communication with the upper end of said chamber, said tube having the upwardly extending portion thereof gradually tapering outward from its lower end to near the upper end thereof, and 50 a burner disposed in said tube.

6. In an apparatus of the class described, a casing, a fire box disposed within said casing and having a grated bottom and side wall, a plurality of burners projected 55 through the side walls of the casing and fire box into the lower portion of the fire box above the bottom thereof, another burner projected into the lower portion of the fire box through the side walls of said casing 60 and fire box, and a tube inclosing said burner and extending upward through the central portion of the fire box and having lateral communication at its upper end with the upper end portion of the fire box chamber. 65

7. In an apparatus of the class described, a casing having a drainage outlet at its bottom, a fire box disposed within the casing and having a grated bottom, a pan supporting grate disposed between the bottoms of said casing and fire box, a pipe disposed below said grate and extending around the marginal portion thereof, said pipe having communication with a source of water supply and having perforations for directing a plurality of streams of water into the lower portion of said casing. 75

In testimony whereof, I have hereunto signed my name to this specification.

RINHOLD W. KRENZ.
